DESIGN FOR WALL-PAPER.

Design No. 13,009, dated June 27, 1882.

UNITED STATES PATENT OFFICE.

EDUARD LEISSNER, OF NEW YORK, N. Y.

DESIGN FOR WALL-PAPER.

SPECIFICATION forming part of Design No. 13,009, dated June 27, 1882.

Application filed April 21, 1882. Term of patent 3½ years.

To all whom it may concern:

Be it known that I, EDUARD LEISSNER, of New York, in the county and State of New York, have invented a new and original Design for Wall-Paper and similar Fabrics, of which the following is a specification.

This invention relates to a new and original design for wall-paper and similar fabrics; and it consists in the novel grouping and configuration of parts, hereinafter more fully described.

The accompanying photograph illustrates a face-view of a wall-paper bearing my new design.

A is a vine-like figure, bearing on it numerous figures resembling leaves, buds, branches, and flowers of various kinds, and which extends over a plain background and forms the design. This vine A has upon it the deeply indented flower-like figure B, from above which extends to the right a tendril bearing leaves and a circular scalloped figure and toward the left a branch bearing upon it the figure H, resembling a flower with leaves like open loops. From this same branch also branches off the figure G, an open flower with long-pointed leaves, somewhat resembling a widely-open tiger-lily, and from a stem extending from this

figure G grows the figure J, resembling a flower with open sharp-pointed serrated petals. On another tendril extending from the figure B grows the flower-like figure C, having triangular petals, and on a stem projecting from this in turn grows the flower-figure D, fan-shaped in form, with leaves resembling open loops. Below the figure B, on a stem projecting therefrom, grows the figure E, fan-shaped, with pointed leaves having open loops. Farther down along the vine A is the figure F, resembling a many-pointed star with circular center, from which branches on one side the flower-like figure L, with loop-like petals, and on the other side a stem which extends into the curved branch I, bearing oblong leaves and bud-like figures upon it. On the vine A, below the figure F, we meet again the figure H and the figure B, already described.

I claim—

The design for wall-paper, consisting of the vine A, containing figures B, H, G, J, C, D, E, F, L, and I, substantially as shown.

EDUARD LEISSNER.
